UNITED STATES PATENT OFFICE

98,150

DESIGN FOR A SHOE OR SIMILAR ARTICLE

Stanley T. Drake, Abington, Mass.

Application November 7, 1935, Serial No. 59,422

Term of patent 14 years

To all whom it may concern:

Be it known that I, Stanley T. Drake, a citizen of the United States of America, residing at Abington, in the county of Plymouth and State of Massachusetts, have invented a new, original, and ornamental Design for a Shoe or Similar Article, of which the following is a specification, reference being had to the accompanying drawing, forming part thereof.

In the drawing,

Fig. 1 is a side perspective view of a shoe or similar article showing my new design; and

Fig. 2 is a perspective view of the opposite side of the disclosure in Fig. 1.

The characteristic features of my design reside in the provision of the half goring on the inside of the shoe of the type shown, the strap passing over the vamp of the shoe and being stitched thereto, the jodhpur or lap opening on the outside of the shoe, and the buckle on the strap for holding the jodhpur opening closed, as shown in Fig. 2 of the drawing.

I claim:

The ornamental design for a shoe or similar article, substantially as shown and described.

In testimony whereof I affix my signature.

STANLEY T. DRAKE.
